ATTORNEY.

UNITED STATES PATENT OFFICE.

CHARLES S. COLEMAN, OF LOS ANGELES, CALIFORNIA, ASSIGNOR TO THE COLEMAN BOILER APPLIANCE COMPANY, OF LOS ANGELES, CALIFORNIA, A CORPORATION OF DELAWARE.

BOILER TUBE AND END-PLATE CONNECTION.

1,340,118.

Specification of Letters Patent.

Patented May 11, 1920.

Application filed February 12, 1917. Serial No. 148,106.

To all whom it may concern:

Be it known that I, CHARLES S. COLEMAN, a citizen of the United States, residing at Los Angeles, in the county of Los Angeles and State of California, have invented a new and useful Boiler Tube and End-Plate Connection, of which the following is a specification.

My invention relates to boiler tube and 10 end plate connections and particularly pertains to improvements in the form of such connections shown in United States Patent No. 949,621, issued to me February 15, 1910.

It is the purpose of my present invention 15 to provide a construction whereby the joint between the tube and end plate will be rendered substantially leak proof and in which expansion and contraction of the tube and the consequent pull and pressure 20 exerted on the joint will not tend to weaken same.

A prime object of my invention is to provide a construction by which the copper gasket commonly employed in such joints 25 will be concealed both interiorly and exteriorly of the end plate so that it will not be subject to the corrosive action of water in the boiler or to the action of flames and gases in the combustion chamber.

30 A further object is to provide a double wedge connection between the tube and end plate by which the tube and plate are securely keyed together and effectively held against separation.

35 Other objects will appear hereinafter.

The invention is illustrated in the accompanying drawings, in which:

Figure 1 is a view in vertical section showing the manner of forming the connection 40 between the tube and the plate.

Fig. 2 is a detail in perspective of the tube point.

Fig. 3 is a detail in perspective showing the formation of the opening in the tube 45 plate for the reception of the tube end.

Fig. 4 is a detail section showing a modified form of the connection.

In carrying out this invention the tube 50 plate 5 is formed with a tube receiving opening having differential diameters to form an annular shoulder 6 a short distance from the marginal edge of the opening on the inner face of the plate. The wall 7 of the opening, extending from the shoulder 6 55 to the outer or fire box face of the plate is

reamed out so that it is larger on the outer side and narrowest at the shoulder, this wall thus being inclined or outwardly divergent.

The wall 8 of the opening, extending from the shoulder to the inner face or water 60 back of the plate is preferably reamed out so as to be slightly wider at its outer edge than adjacent the shoulder as shown in Fig. 1, thus forming the walls 7 and 8 of the differential diameters of the opening to 65 diverge oppositely to each other and thereby present opposite inclined faces through any section of the edge of the opening.

The tube end 9 is formed with a reduced portion 10 terminating at its inner end in a 70 shoulder 11 and the outer surface of the tube is slightly beveled at its juncture with the shoulder 11 to conform with the bevel of the wall 8. However, the bevel of the wall 8 and the tube may be dispensed with 75 and this wall of the inner portions of the opening formed of equal diameter throughout so as to conform to the tube with a driving fit, as shown in Fig. 4.

In making the joint, a copper gasket 12 hav- 80 ing an outwardly extending annular flange 13 on one end thereof is inserted in the large end of the opening to seat the flange 13 on the shoulder 6. The outer portion of the gasket is then rolled to conform to the wall 7 and 85 the outer edge of the gasket is beaded over the outer marginal edge of the opening.

The reduced end of the tube is then inserted through the opening from the inside of the plate with the shoulder 11 abutting 90 against the flanged end of the gasket; the end of the tube being driven tight against the wall 8 of the opening so as to conceal the inner end of the gasket and protect it from corrosive action of water in the boiler. 95 The reduced portion of the tube is then rolled to conform to the inclined wall 7 and the gasket thereon, thus flaring the end of the tube as shown in Fig. 1. This flare of the tube forms a wedge which opposes withdrawal of the tube and serves in coöperation with the shoulders to bind the tube in close engagement with the plate.

The outer end of the tube is then beaded over, as indicated at 14, as is common in 105 boiler construction, and this bead is extended to cover the outer end of the gasket and protect it against direct action of heat and gases in the combustion chamber.

The action of the joint is as follows: Lon- 110

5 longitudinal expansion of the tube causes the shoulder 11 thereof to bear upon the shoulder 6 of the plate through the flange of the gasket, thus not tending to shift the tube
10 5 in its joint nor to force the beaded end thereof away from the outer face of the plate. Inward pull of the tube caused by longitudinal contraction thereof is delivered to the plate through the bead and throughout the beveled wall 7. This prevents any tendency of the shoulder 11 of the tube to pull away from its seat.

15 The diametrical expansion and contraction of the tube in relation to the plate will be very slight if any; but such as might occur will not tend to separate or open the joint by reason of the contacting shoulders of the tube and plate being held in close engagement by the action of the flared and 20 beaded connection between the outer portion of the tube and plate.

25 From the foregoing it will be seen that I have provided a tube and sheet connection for boilers which is durable and practically non-leakable.

I claim:

1. The combination with a tube sheet having an opening of differential diameters to form an annular shoulder between the ends 30 of the opening, the side walls of the opening on opposite sides of the shoulder being beveled outwardly forming oppositely inclined walls, of a soft metal gasket comprising a cylinder having a flange on one end adapted 35 to seat on the shoulder, said gasket formed to conform to the outer inclined wall of the opening and beaded over the margin of the latter, and a tube point having a reduced portion at its outer end, the same terminating 40 in a shoulder adapted to seat on the flange of the gasket, and having a beveled wall conforming to the inner beveled wall of the opening, the outer end of said tube being turned outward against the gasket 45 and beaded over the outer end of the latter.

2. The combination of a tube sheet having a flue end receiving opening the walls of which taper and converge from the outside of the tube sheet inward, a counterbore 50 around the margin of the opening on the inner face of the tube sheet the walls of which taper and converge from the inner face of the tube sheet, a shoulder at the convergent ends of the opening and counterbore 55 facing the inside of the sheet, a soft metal gasket having a cylindrical wall terminating at one end in an outward flange, said gasket arranged with the flange seating on the countersunk shoulder and with the wall 60 of the gasket expanded over the tapered wall of the opening and with its outer end beaded over the outer face of the tube sheet, and a flue point of an outside diameter to fit the counterbore and having a reduced end 65 portion with a shoulder at the base of the

reduced portion, said shoulder abutting on the flange of said gasket and the reduced portion expanded to flare outwardly against the gasket throughout the width of the opening wall, the outer end of the flue point 70 beaded over the bead on the gasket and onto the outer face of the tube sheet to conceal the gasket bead.

3. The combination of a tube sheet having a flue end receiving opening the walls 75 of which taper and converge from the outside of the tube sheet inward, a counterbore around the margin of the opening on the inner face of the tube sheet, a shoulder at the convergent end of the opening at the 80 base of said counterbore facing the inside of the sheet, a soft metal gasket having a cylindrical wall terminating at one end in an outward flange, said gasket arranged with the flange seating on the shoulder and 85 with the wall of the gasket expanded over the tapered wall of the opening and with its outer end beaded over the outer face of the tube sheet, and a flue point of an outside diameter to fit the counterbore and having 90 a reduced end portion with a shoulder at the base of the reduced portion, said shoulder abutting on the flange of said gasket and the reduced portion expanded to flare outwardly against the gasket throughout 95 the width of the opening wall, the outer end of the flue point beaded over the bead on the gasket and onto the outer face of the tube sheet to conceal the gasket bead.

4. The combination of a tube sheet having a flue end receiving opening the walls of which taper and converge from the outside of the tube sheet inward, a counter-bore around the margin of the opening on the inner face of the tube sheet, a shoulder at 100 the convergent end of the opening at the base of said counterbore facing the inside of the sheet, a soft metal gasket having a cylindrical wall terminating at one end in an outward flange, said gasket arranged 105 with the flange seating on the shoulder and with the wall of the gasket expanded over the tapered wall of the opening and with its outer end beaded over the outer face of the tube sheet, the flange on said gasket having 110 a thickness less than the depth of the counterbore so that its outer face will be counter-sunk within the counter-bore, and a flue point of an outside diameter to fit the counter-bore and having a reduced end 115 portion with a shoulder at the base of the reduced portion, said shoulder abutting on the flange of said gasket concealing the flange within the counterbore, the reduced portion of said flue point expanded to flare outwardly against the gasket throughout the width of the opening wall, the outer end of the flue point being beaded over the bead 120 on the gasket and onto the outer face of the tube sheet to conceal the gasket bead. 125

5. The combination of a tube sheet having a flue end receiving opening, a counterbore around the margin of the opening on the inner face of the tube sheet, a shoulder 5 at the base of said counterbore, a soft metal gasket having a cylindrical wall terminating at one end in an outwardly projecting flange adapted to seat on said shoulder with the wall of the gasket extending over the 10 outer portion of the wall of the opening, said flange having a thickness less than the depth of the counterbore so that its outer face will be countersunk within the counterbore, and a flue point of an outside diameter to fit the counterbore and having a reduced 15 portion with a shoulder at the base of the reduced portion, said shoulder abutting on the flange of said gasket and concealing the flange within the counterbore.

CHARLES S. COLEMAN.
